[57] CLAIM

The ornamental design for a cart for transporting people, as shown and described.

DESCRIPTION

FIG. 1 is a front perspective view of a cart for transporting people showing my new design.

FIG. 2 is a rear perspective view thereof.

FIG. 3 is a side perspective view thereof, the opposite side being a mirror image thereof.

FIG. 4 is a front elevational view thereof.

FIG. 5 is a rear elevational view of a cart for transporting people showing a second embodiment, the sole difference from the first embodiment being in the canopy and the carrying basket attached under the seat.

FIG. 4

FIG. 1

FIG. 3
